FLOAT

Clare W. Webber, Cedar Rapids, Iowa

Application July 16, 1934, Serial No. 735,341

2 Claims. (Cl. 9—17)

This invention relates to floats generally and has more particular relation to floats adapted for use by children.

While various floats have been proposed for supporting the body of a person in the water, such devices have not always proven satisfactory; first, for the reason that they were not adapted for children, and second, there were not sufficient practicable means for holding the child in the float so that it would not be able to get out or could not possibly work itself out of the float. While tubes of rubber and the like have been employed there has been no provision for maintaining the device in floating position and maintaining the child above the water if the tube became deflated. Furthermore, such devices when attached to rubber tubes, were attached only at narrow sections of the tube and the tube could belly up between the supports. Furthermore, the means of engagement of the supports to the tube frequently were such that chafing of the tube resulted with consequent destruction of the usefulness of the device.

I have observed the difficulties of the devices of the prior art and have devised a device for overcoming these difficulties. It is therefore a general object of my invention to provide an improved, new and novel float for supporting children in the water.

It is a more particular object of my invention to provide efficient and satisfactory means for engaging the child in the float.

Another object of my invention is to provide auxiliary supporting means for supporting the child in the water even if the main supporting means becomes inoperative.

Another object of my invention is to provide, in a float employing a tube, means for engaging the support to the tube which will obviate chafing of the tube and will not permit it to belly up between the supports.

Another object of my invention is to provide a continuous supporting means for engaging the tube of such a device.

Other and further features and objects of the invention will be more apparent to those skilled in the art upon a consideration of the accompanying drawings and following specifications, wherein is disclosed a single exemplary embodiment of the invention, with the understanding however, that such changes may be made therein as fall within the scope of the appended claims, without departing from the spirit of the invention.

Referring now to the drawing, Figure 1 is a view in perspective of a device constructed ac-

cording to a preferred embodiment of my invention.

Figure 2 is a view partly in elevation and partly in section, of a device shown in Figure 1.

Figure 3 is a partial view of a device constructed according to another embodiment of my invention wherein a modified float engaging support is employed, and

Figure 4 is a partial view of still another embodiment of my invention in which a still further modified form of float and float engaging means is employed.

Referring now more particularly to Figures 1 and 2 of the drawing, there is shown at 10 a circular tube which, in this preferred embodiment of my invention, is constructed of a resilient material such as rubber, waterproof fabric or the like and which may be filled with air or other gas through the valve 11 to hold it in distended position. The inner tube usually employed for automobile tires forms a very good float for the purpose. This float 10 may be termed the "main" float and it is this float which normally supports the weight of the child in the water.

In order to furnish means for engaging this support I preferably employ a ring-like top or flat circular member 12 of wood or like material to make it lighter than water so that it will have a buoyant effect. The outer diameter of the member 12 is preferably slightly greater than the outer diameter of the tube and the inner diameter of which is preferably slightly less than the inner diameter of the tube.

In order to prevent the tube from bellying up between the supports for engaging the chair I preferably make this circular member 12, which may be termed the auxiliary float, an entire ring. In order that this auxiliary float may be strong and may furnish a stronger support at the point where it engages the tubular member 10 and also in order to make this auxiliary float so that it may be dismounted to take only a small space I preferably employ arcuate sections 12a. A preferred number of sections is six but of course any number may be employed. These sections 12a may be secured to each other by securing means indicated at 13, which may take the form of clinched nails or split rivets, or bolts and wing nuts to facilitate taking the float apart.

The main float 10 is preferably engaged to the auxiliary float 12 by means of wire straps 14 which are fastened to the under side of the auxiliary float by screws 16 or other suitable fastening means. These straps are preferably U-shaped and encircle the main float. They are

preferably fastened to the auxiliary float at the junction of the sections, such as sections 12a and 12b, and if desired bolts and wing nuts may be employed in place of the screws 16 and these 5 fastening means may be employed not only to engage the main float to the auxiliary float but also to hold the various sections 12a, 12b and so on, together.

The child is preferably supported by means of 10 a saddle-like member 17 disposed centrally of the main and auxiliary floats and located in a plane well below these floats so that the device will not tip over in use. In supporting the saddle member 17 I preferably employ a plurality of 15 L-shaped metal strap-like members 18. These members are preferably radially located and are preferably fastened to the upper faces of the lower arcuate members, as for instance the members 12b, 12d, and 12f, and preferably extend in 20 the same horizontal plane inwardly to points just above the outer edge of the saddle 17, then downwardly over the edge of the saddle as indicated at 18b, and then inwardly beneath the saddle as indicated at 18c. The portions 18c of the supports 25 18 are preferably fastened beneath the saddle 17 by means of any suitable fastening means such as screws, nails, bolts, or wing nuts, as indicated at 19.

The portions 18a and 18b of the supports 18 30 are preferably separable and may be engaged to each other as by means of rivets 20 or bolts and thumb nuts as desired so that the device may be made dismountable and may be adjustable in length to raise and lower the saddle with reference to the floats for different aged children.

A circular strap 21 is preferably secured to the member 18 at the point where they turn downwardly and this strap 21 serves the double function of making the supports rigid and of engaging 40 the body of the child so as to hold him in position so that he cannot get out of the float either accidentally or through his own efforts. As an additional precaution the strap 22 of leather, webbing, or the like may be engaged on 45 the supports 18 just above the circular strap 21 and may be more tightly engaged about the child to positively hold him in place in the float.

It may readily be understood that the device 50 may be assembled and disassembled and adjusted for various ages of children. The device will float even if the main float is punctured or otherwise rendered inoperative and thus support the child in the water even if the main float is deflated. The device forms a rigid support for the 55 child which cannot be overturned particularly as the saddle is always at the center of the device well below the floats. The circular strap 21 is

of importance in securing this result since it limits the movement of the child which might tend to overbalance the device.

In Figure 3 I have illustrated another embodiment of my invention in which the circular member 5 or auxiliary float 12 is replaced by a metal member 31. This metal member 31 is a ring-like member which is concaved at the under side as illustrated at 32. The member 31 is preferably provided with beads 33 at either edge thereof and 10 a strap 34 is employed for holding the tubes 36 in place beneath the member 31. The supports 37 corresponding to the members 18 shown in Figure 1, are preferably secured to the under side of the member 31 and are curved to conform 15 to the concave surface of the member. This device has the advantage of the engagement of the tube 34 through a relatively large portion of its surface and the device makes a pleasing appearance when constructed in this manner. 20

I have shown still another embodiment of my invention in Figure 4 of the drawing. A tube 41 preferably of metal is employed for the main float and the supports 42 corresponding to the supports 18 of Figure 1 are preferably engaged to 25 the tube 41 as by means of spot welding or the like as indicated at 43. A device constructed in accordance with this embodiment of my invention may be plated with metal or chromium plating and thus may be made to have a very pleasing 30 appearance.

Although I have described several embodiments of my invention I do not wish to be limited thereto, since modifications thereof may be made by those skilled in the art and such modifications 35 may be made without departing from the spirit and scope of the invention as set forth in the appended claims.

I claim as my invention:

1. In a float, a main float, an auxiliary ring-like float made up of sections of buoyant material in order that it may be easily dismantled, fastening means for securing the sections together, L-shaped supports engaged to the auxiliary float, and a saddle-like seat adjustably secured to the L-shaped supports to accommodate various sized users. 40

2. In a float, a circular tube-like float, a ring-like metal member disposed over the circular float, said member being of thin arcuate cross-sections, U-shaped wire members engaging the ring-like member to the tube-like float, rigid L-shaped supports engaged to the ring-like member, and an adjustable saddle-like seat secured to the L-shaped supports. 50 55

CLARE W. WEBBER.
